UNITED STATES PATENT OFFICE

105,532

DESIGN FOR A GAS RANGE

Frederic A. Leisen, Detroit, Mich., assignor to
Detroit-Michigan Stove Company, Detroit,
Mich., a corporation of Michigan

Application March 22, 1937, Serial No. 68,346

Term of patent 14 years

To all whom it may concern:

Be it known that I, Frederic A. Leisen, a citizen of the United States of America, residing at Detroit, in the county of Wayne and State of Michigan, have invented a new, original, and ornamental Design for a Gas Range, of which the following is a specification, reference being had therein to the accompanying drawing forming a part thereof, wherein:

The figure is a perspective view of a gas range embodying my new design.

The other side of the gas range is like the side shown.

The dominant feature of my design consists in the inverted trough-shaped base.

I claim:

The ornamental design for a gas range substantially as shown and described.

FREDERIC A. LEISEN.
